UNITED STATES PATENT OFFICE.

ANTON GUNTHER, OF TORONTO, ONTARIO, CANADA.

DESIGN FOR A PIANO-CASE.

SPECIFICATION forming part of Design No. 15,052, dated June 10, 1884.

Application filed February 11, 1884. Term of patent 3½ years.

Registered in Canada February 19, 1884, No. 4.

To all whom it may concern:

Be it known that I, ANTON GUNTHER, a subject of the Crown of Great Britain, residing at Toronto, Canada, have invented and produced 5 a new and original Design for a Piano-Case, of which the following is a specification, reference being had to the accompanying drawing, forming part thereof.

The figure is a perspective view of my improved design for an upright-piano case.

The supports or legs B B' and cover C for the key-board are of any approved pattern, and form no part of my design; but the case A, which contains the strings, sounding-board, 15 hammers, &c., is in vertical outline, when viewed from front or back, shaped like an irregular pentagon or five-sided figure, 1 2 3 4 5, of which the sides 1 and 3 are longer than the rest. The lower side, 3, of the case, as 20 shown, is slightly inclined to the horizontal and the end portions, 4 and 5, project on the right hand beyond the leg or support B' on that side a greater distance than the end 2 does on the left of leg or support B. The side 25 5 of the pentagon is, for graceful effect, preferably curved: Of the two longest sides 1 and 3 of the figure, 1 is a horizontal line, and 3 approximates a horizontal line. The cover

C for the key-board is, as will be seen, comprehended within the limits of the circumscribed lines of the pentagon. 30

What I claim is—

1. As a new design, an upright-piano case consisting of an irregular pentagonal figure, when viewed from the front, with one of its two longer sides horizontal, and the other nearly so, and its key-board cover included within the limits of the circumscribed lines of the pentagon, as shown. 35

2. As a new design, an upright-piano case 40 of pentagonal form, having one portion of the same projecting beyond the legs or support at one end a greater distance than the other end does beyond the legs at that end, as shown.

3. As a new design, an upright-piano case 45 of pentagonal form, having the key-board cover included within the limits of the pentagonal figure, and one end of the pentagon projecting a greater distance beyond the legs at that end than the other end projects beyond the legs at that end, as shown. 50

ANTON GUNTHER.
